S. M. JOHNSON,
CONVERTIBLE RAFT AND THE LIKE.
APPLICATION FILED MAR. 4, 1918.

1,274,273.

Patented July 30, 1918.

UNITED STATES PATENT OFFICE.

SAMUEL MATHEW JOHNSON, OF CARDIFF, WALES, ASSIGNOR TO JOHNSON'S CONVERTIBLE BOATS AND RAFTS LIMITED, OF CARDIFF, WALES.

CONVERTIBLE RAFT AND THE LIKE.

1,274,273.

Specification of Letters Patent.

Patented July 30, 1918.

Application filed March 4, 1918. Serial No. 220,208.

To all whom it may concern:

Be it known that I, SAMUEL MATHEW JOHNSON, a subject of the King of Great Britain, and resident of 15 Neville street, 5 Cardiff, in the county of Glamorgan, Principality of Wales, in the Kingdom of Great Britain and Ireland, have invented a certain new and useful Improvement to or Connected with Convertible Rafts and the like, 10 of which the following is a specification.

This invention relates to a structure adapted for use alternatively as a ship's life-saving raft or as a deck-fitting constituting a canopy-seat, alcove or shelter for passengers on ship-board; the object of the invention being to provide a structure which, while capable of being secured on deck close to the bulwarks or side hand-rail, can be readily cast loose and without further preparation thrown overboard where, being self-righting, it will at once constitute a raft presenting a well for the accommodation of passengers.

In a practical form, the structure of the 25 present invention consists of an oblong and substantially rectangular hollow body which (regarded on the one hand as a raft) has approximately flat sides and ends and is closed at bottom and open at top so as to 30 present a well, the structure carrying at or near its lower longitudinal angles (whereat the bottom meets the respective sides) a pair of buoyancy-pontoons, and which (regarded on the other hand as a deck-fitting) 35 is adapted for being set up on deck so as, by resting upon one of its longer sides, to present an alcove or shelter open at front and closed at the rear and ends and at its upper and lower sides. In addition a pair of seat- 40 lockers, either or both of which may be slideable transversely of the interior of the structure on guides, are provided so that, when the structure is used as a raft, the lockers may form benches face-to-face at the respective 45 sides of the well whereas, when the structure is used as a deck-shelter, the one locker will be superposed on the other at the lower side of the structure to form a single bench.

50 In the accompanying drawings, which illustrate in a somewhat elementary manner one embodiment of the invention, Figure 1 is a midship cross-section of the structure when set afloat for use as a raft, Fig. 2 being 55 a similar view showing the structure when

set up on deck for use as a canopy-seat or shelter. Fig. 3 is a plan view of the structure when used as a raft, while Fig. 4 is a front elevation of the structure when used as a canopy-seat or shelter. 60

The structure shown in the drawings consists inwardly of an oblong rectangular open-topped box having a bottom 11, a pair of longer sides 12, 12, and a pair of shorter ends 13, 13; the ends 13, 13 being obtusely 65 wedge-shaped externally so as to present each a blunt cut-water 14. The sides of the structure are duplex and each incloses between its inner wall 12 and its outer wall 15 a hollow watertight space 16 adapted to 70 contain a mast, oars, or other necessary fittings for use when the structure is employed as a raft, the space 16 at each side being closed at top preferably by a sliding door or doors 17. 75

The outer walls 15, 15 of the sides of the structure are inwardly curved so as to converge slightly in the downward direction and thus give to the structure the cross-sectional form of a flat-bottomed boat, as indicated in Fig. 1, and outside each lower longitudinal angle is fixed (by means of brackets as indicated at 18) a buoyancy-pontoon consisting of a closed metal cylinder 19 with domed ends 20, both pontoons 80 extending throughout the length of the structure. Each pontoon is so placed relatively to the inward curvature of the adjacent outer side-wall 15 that the structure, when set up on deck so as to rest on one of 85 the side-walls 15, will be kept erect by resting also on the pontoon as indicated in Figs. 2 and 4, wherein 21 represents the deck while 22 represents a gunwale of the ship, the structure being shown as placed with 90 what is now the back 11 of the shelter thus constituted, turned outboard.

Internally, the structure is provided with a pair of seat-lockers 23, 24 which extend throughout the length of the well of the raft 100 and either or both of which may be slideable transversely thereof on guides 25 at the ends 13, 13 so that, when the structure is used as a raft, the respective lockers can be placed at opposite sides of the well to serve as 105 separate benches as indicated in Figs. 1 and 3, whereas, when the structure is used as a deck-shelter, the lockers will be superposed one upon the other at the (for the time being) lower side of the interior of the shelter, 110

and will thus form together a single bench as indicated in Figs. 2 and 4. The lockers are preferably furnished with sliding doors as indicated at 26, and, when placed at the 5 sides of the well of the raft, would be secured in position by catches, lashings, or other convenient means.

When the structure is set up on deck as in Figs. 2 and 4, it is secured in position 10 (by lashings for example) so that, on being cast off, the structure can be tipped overboard instantly without further preparation, when it will at once right itself in the water in readiness to receive passengers.

15. I claim:—

1. A structure adapted to serve as a raft or a covered deck seat, comprising a boat-like body having water-tight compartments in its sides closed by doors, and provided 20 with pontoons secured thereto at the junction of its bottom and sides, and with two longitudinally extending seat-lockers, one of which is transversely slidable to permit it to rest on the other when the structure is 25 used as a covered seat.

2. A structure adapted to serve as a raft or a covered deck seat, consisting of an oblong and substantially rectangular body having approximately flat sides and ends, 30 the structure being closed at the bottom and

open at the top so as to form a well, pontoons secured to the body at the junction of its bottom and sides, and a seat locker at each side of the body and extending the length thereof, one of the lockers being 35 mounted to slide transversely to rest upon the other locker when the structure is placed on its side and used as a covered seat.

3. A structure adapted to serve as a raft or a covered seat, consisting of a substantially rectangular body having approximately flat sides and ends, the structure being closed at the bottom and open at the top so as to form a well and provided at the junction of its sides and bottoms with 40 pontoons whose outer faces lie in the same plane as the sides, whereby the structure is adapted to rest on one side to form a shelter open at the front and closed at the rear ends, and its upper and lower sides. 45

4. The combination with a boat-like structure adapted to serve as a raft or as covered deck seat, of a pair of seat-lockers either or both of which may be slidable transversely of the interior of the structure on guides 50 so as to be adapted for use alternatively as separate benches in the raft or as a single bench in the deck-shelter, substantially as described.

SAMUEL MATHEW JOHNSON.
